UNITED STATES PATENT OFFICE.

ELLERSON L. BRAINARD, OF DANBURY, CONNECTICUT, ASSIGNOR TO THE
ROGERS SILVER PLATE COMPANY, OF CONNECTICUT.

DESIGN FOR AN INKSTAND.

SPECIFICATION forming part of Design No. 34,158, dated March 5, 1901.

Application filed December 21, 1900. Serial No. 40,694. Term of patent 3½ years.

To all whom it may concern:

Be it known that I, ELLERSON L. BRAINARD, a citizen of the United States, residing at Danbury, in the county of Fairfield and State of Connecticut, have invented and produced a new and original Design for Inkstands, of which the following is a specification, reference being had to the accompanying drawings, forming part thereof.

10 Figure 1 is a front view of an inkstand, showing my new design. Fig. 2 is a side view.

As shown in the drawings, the inkstand rests upon a square base supported on four feet—two in front and two in rear. In the center 15 of the base, on the front edge, is the head of a dragon and on either side a semicircular decoration. Back of this is the depression or hollow, in which a glass well rests. The glass well has an outer rim, and this rim rests in 20 a round holder, which is recessed to support the well. The well has a detachable cover without pivot or hinge. This cover is ornamented by a bust of a mermaid raised above the surface, with the tail twined around the 25 edge of the cover. The ornamentation of the cover affords a grasp by which it is raised. On either side of the well is a depression in the shape of a sea-shell. The rear of the stand is formed by a dragon, the head on a line with

and to the right of the cover. The right foot 30 of the dragon rests in rear of the depression on the right of the well, the left foot passing to the left of the well just behind the depression on that side. The body of the dragon is immediately behind the cover. In rear of the 35 head are two wings rising from the body of the dragon, and on a line to the left of the wings the tail of the dragon stands erect. A line drawn between the head and wings, if prolonged, passes between an opening in the 40 tail.

As shown in the drawings, the leading or material feature consists of a pen-rack formed by the wings and tail of the dragon and one formed by the ornamentations at the base of 45 the well in front.

Having described my invention, what I claim as new, and desire to secure by Letters Patent, is—

The design for an inkstand, as herein shown 50 and described.

In witness whereof I have signed my name to this specification in the presence of two subscribing witnesses.

ELLERSON L. BRAINARD.
